Arthur V. Hansa, West Los Angeles, Calif.

Application April 4, 1949, Serial No. 1,793

Term of patent 3½ years

(Cl. D14—3)

To all whom it may concern:

Be it known that I, Arthur V. Hansa, a citizen of the United States and resident of the city of West Los Angeles, county of Los Angeles, State of California, have invented a new, original, and ornamental Design for a Shopping Cart, of which the following is a specification, reference being had to the accompanying drawing, forming a part thereof, in which:

Fig. 1 is a plan view of a shopping cart embodying my new design;

Fig. 2 is a front end elevational view;

Fig. 3 is a rear end elevational view; and

Fig. 4 is a side elevational view.

The characteristic features of my design reside in the portions shown in full lines in the drawing.

I claim:

The ornamental design for a shopping cart, substantially as shown and described.

ARTHUR V. HANSA.
